UNITED STATES PATENT OFFICE.

CLIFFORD G. MICKEL, OF BERRYTON, KANSAS.

TRIANGLE.

Application filed June 7, 1928. Serial No. 114,177.

My invention relates to triangles, and has for its chief object the embodiment of a protractor and beam compass connecting with the triangle.

5 A further object of my invention is to provide a drafting instrument that is not cumbersome, and adaptable for students' use.

A still further object of my invention is 10 to provide a protractor within a triangle having a complete visibility with isolated center and a bevelled edge for accurate reading.

A still further object of my invention is 15 to provide a beam having apertures longitudinally spaced thereon adaptable for pencil or crayon in the process of drawing circles.

These and other objects will hereinafter be more fully explained.

20 Referring to the drawings:

Fig. 1 is a plan view of the triangle.

Figure 2 is a cross section taken on line 2-2 in Fig. 1.

The instrument herein disclosed consists 25 of a triangle 1 having centrally positioned therein an opening 2, said opening being an arc and having degree graduations 3 around the circle thereof functioning as a protractor of 180 degrees. The periphery of the arc 10 being bevelled as at A so that the graduations extend to close contact with the surface on which the triangle is placed.

Spaced from the base or diametrical axis of the protractor is one wall of the opening 15 as at B. Laterally extending therefrom and centrally positioned thereon is a tongue 4 having an aperture 5 therein, the center of which is on the base line of the protractor. The said aperture being the pivot point of 40 a beam 6, the said beam adapted to revolve being connected thereto by an eyelet 7.

That end of the beam having parallel edges as at C has a plurality of apertures 45 adapted to receive the end of a crayon as centering means when drawing a circle; the opposite end of the beam being pointed so that one edge as at D is radially positioned with the graduations of the protractor, and in alignment with said edge is a line E on 50 opposite sides of the aperture and diametrically positioned therewith. Similar lines F are transversely positioned to the first said lines, the said lines function as cross hairs when placing the center of the protractor 55 on a given point which is visible through the eyelet 7. The pointed end of the beam

has a plurality of staggered apertures 9 to receive the point of a pencil when making circles of different diameters. Note that the beam will describe an entire circle as 60 partly indicated by dotted line G; one position being shown by dotted line H.

Measurement graduations may be placed along the angles of the triangles as shown at 10. I do not confine the measurements 65 to the hypotenuse angle as shown in the drawings as they may be placed along the right angles. Neither do I confine the graduations to any particular system, as the metric system may be applied on one or more 70 of the angles as well as the United States standard system.

It will be understood that the instrument may be applied on blackboards as well as working on a drawing table or desk and will 75 be very useful to professional draftsmen or students, as the instrument may be used as a triangle or a protractor and circles of different diameters may be made within the scope 80 of the instrument when an ordinary compass is not available.

To establish angles of different degrees from a given base line, the base of the protractor will be placed registering with the line and if a perpendicular line is to be considered in connection therewith the intersection of the lines are visible through the eyelet at which time the vertical cross hair will assist in the alignment. It being understood that the edge D of the beam will 90 register with 180 degrees and the opening extending below 180 degrees provides an unobstructed view of the base line, therefore the instrument can be set more accurately.

Such modifications may be employed as 95 lie within the scope of the appended claims.

Having thus described my invention, what I claim as new and desire to secure by Letters Patent is:—

1. In a triangle, a drafting instrument 100 having an arcuate opening, a beam having a laterally extending member provided with an aperture, the center of the aperture being in alignment with the straight edge of one end of the beam, there being a bevel 105 on the peripheral edge of the arcuate opening, said bevel having degree graduations thereon to provide a protractor the aligned edge of the beam with the said aperture comprising radial means for finding the degree 110 of an angle, there being cross lines on the laterally extending member of the beam,

said lines being transversely positioned to each other adjacent the pivot and functioning as a cross hair for centering the aperture on a given point when the straight side of the beam is rocked to alignment with its respective plane of the triangle.

2. In a drafting instrument, a triangular member having an arcuate opening therein, one edge of the opening being beveled, there being graduations on the bevel spaced as degrees and functioning as a protractor, a beam having a lateral extension apertured for a pivot point, said extension being centrally positioned on the beam, edges of the beam on one side of the pivot point being parallel

and having apertures centrally and longitudinally spaced, the opposite end of the beam converging to an apex one edge thereof being positioned radially of the aperture in the lateral extension, there being two rows of apertures paralleling the radial edge, the apertures being staggered, an eyelet pivotally securing the beam to the member, the said pivot point being at the center of the arcuate opening, there being cross lines 25 radially extending from the center of the eyelet and in alignment with the inside or radially positioned edge of the beam.

CLIFFORD G. MICKEI.
